UNITED STATES PATENT OFFICE

100,246

DESIGN FOR A TEXTILE FABRIC OR SIMILAR ARTICLE

Paul Reiman, New York, N. Y.

Application May 2, 1936, Serial No. 62,444

Term of patent 3½ years

To all whom it may concern:

Be it known that I, Paul Reiman, a citizen of Germany, residing at 240 West End Avenue, city of New York, county of New York, and State of New York, have invented a new, original, and ornamental Design for a Textile Fabric or Similar Article of which the following is a specification, reference being had to the accompanying drawing, forming a part thereof.

The figure is a plan view of a textile fabric or similar article showing my design.

The area within the dot and dash lines shows one complete unit of the design. The repeats are arranged in vertical rows and adjacent vertical

rows are one-half a complete unit offset so that the angle of the complete unit indicated by letter *a* corresponds with the angle *b* of one of the repeats in an adjacent vertical row.

The design represents a pine needle appearance, the curved and straight lines representing pine needles dispersed in irregular groups over a shaded background.

I claim:

The ornamental design for a textile fabric or similar article as shown and described.

In testimony whereof I have signed this specification.

PAUL REIMAN.
